UNITED STATES PATENT OFFICE

2,089,285

CIRCUIT BREAKER

Humphreys Milliken, Montreal, Quebec, Canada

Application June 27, 1934, Serial No. 732,737

10 Claims. (Cl. 200—81)

This invention relates primarily to circuit breakers used for interrupting heavy short-circuit currents on large power systems. An important object of the invention is to eliminate the fire hazard of oil commonly used for extinguishing the arcs in the interruption of such currents. In this invention, compressed air is used instead of oil for extinguishing the arcs. Compressed air circuit breakers which have heretofore been used have certain weaknesses and limitations, to overcome which, is an important purpose of this invention. With any type of circuit breaker it is necessary to provide a disconnecting switch in series with the circuit breaker in order to isolate the breaker from the live circuit when maintenance work is required. The invention provides for removal of voltage stress with great rapidity by improved coordination of current-interrupting means and a disconnecting switch. Another important object of the invention is to provide an improved circuit breaker designed to facilitate building up of a current interrupter assembly to accommodate increases in voltage. Other objects of the invention will appear hereinafter.

In the drawings:

Fig. 1 shows diagrammatically the general arrangement of the circuit-breaker in the circuit, with its auxiliary equipment in closed position.

Fig. 2 is an end elevation, Fig. 3 a front elevation, and Fig. 4 a top plan, of one form of the circuit-breaker shown schematically in Fig. 1, this form being particularly adapted for use with circuits carrying voltages of the order of 132,000 to 154,000 volts.

Fig. 5 is an end elevation, Fig. 6 a front elevation, and Fig. 7 a top plan of another form of the circuit-breaker, this form being particularly adapted for use with circuits carrying voltages of the order of 275,000 volts.

Fig. 8 illustrates the construction, in elevation and partially in section, of a transformer employed with my circuit-breaker.

Fig. 9 shows schematically in plan the arrangement of the primary winding of the transformer shown in Fig. 8.

Fig. 10 is a horizontal section through an air channel of my current-interrupter, taken on the line 10—10 of Fig. 13.

Fig. 11 is a vertical section through my current-interrupter, taken on line 11—11 of Fig. 10.

Fig. 12 is another horizontal section through an air channel, taken on the line 12—12 of Fig. 13.

Fig. 13 is a vertical section on line 13—13 of Fig. 12, the damper 32 being open or removed to show the grid 31.

Fig. 14 is a vertical section on the line 14—14 of Fig. 10. 5

Fig. 15 is a vertical sectional view of the air valve used in conjunction with my circuit-breaker.

Fig. 16 is a diagram of a means for opening the automatic disconnecting switch.

Referring to Fig. 1, the main, high voltage, 10 alternating current may be considered as coming in from the main line on the left of the figure, to insulator 140, passing through the automatic disconnecting switch 1, through a transformer 2, thence through an automatic transfer switch or by-pass switch 3, thence through a current transformer 4, a non-automatic disconnecting switch 5 to the outgoing main line on the upper right of the figure. Transformer 2 is alternative to transformer 4, only one being required. In shunt with by-pass switch 3 is the current interrupter K which includes contacts 6, movable contacts 7, held closed by springs 8, current-reducing resistors R1 and R2, potential-equalizing-resistors R3, and resistor-tap-contacts 25 9 and 9a.

As shown in Figs. 1 and 4, the disconnecting switch 1 includes a horizontal switch blade 1c, which in closed position engages a contact borne by an insulator 140. The blade forms part of a 30 horizontally foldable linkage mechanism including the links 1b and 1d and the lever 1a. Link 1b is pivotally connected at one end to a crank arm which is rotatable about a vertical axis by rotation of an insulator stack 14. The opposite 35 end of link 1b is pivotally connected to one end of the lever 1a whose opposite end is in turn pivotally connected to the inner end of the switch blade. Between its ends, the lever 1a is pivotally supported or fulcrumed at a fixed point. The 40 link 1d is pivotally connected at one end to the switch blade at a point spaced inward from the connection of the lever 1a with the blade. At its opposite end the link 1d is pivotally supported at a fixed point. The switch blade is shifted to 45 open position by rotation of the insulator stack 14, through 180°. The link 1b is so arranged as to dispose its ends on dead centre with respect to the axis of insulator 14 in both the open and closed positions of the switch blade, thereby locking 50 the switch mechanism against accidental drifting. The purpose of the folding mechanism is to maintain the same space between phases with the switch open or closed, and at the same time provide for horizontal movement of switch 55

blade which is simpler than a vertical movement in connection to rotating stack 14 and eliminates counter-balancing of weight of blade.

The automatic opening of the circuit-breaker takes place as follows: The occurrence of abnormal current in the main line induces abnormal potential in the secondary winding of transformer 2, or in the transformer 4, operates a relay which may be of any well-known type, opening an automatic air-valve 17 (described elsewhere in this specification), admitting a blast of compressed air through an insulating tube 18 to piston 10, forcing it outward, opening by-pass switch 3, then opening movable contacts 7, and then opening automatic disconnecting switch 1. Switches 1 and 3, therefore, break no current. Switch 1 is opened thus: The application of air pressure to piston 11 moves it and slide valve 12 to the left, admitting compressed air from the tank 16 to the upper end of the cylinder 13, moving its piston downward, rotating insulator 14 (preferably 180 degrees), swinging switch blade 1c to open position by means of the linkage 1b, 1a and 1d. Although air pressure reaches piston 11 about a hundredth of a second before it reaches piston 10, switch 1 opens later than switch 3 because of the much greater inertia of the parts to be moved to open switch 1. The parts of switch 1 and the moving parts of its operating mechanism are all mounted to shift horizontally and their shift is unbiased in either direction. Switch 3 and piston 10 are omitted except in case the normal current required to be carried by the circuit breaker is in excess of about 600 amperes. The opening of the automatic air blast valve opens the electric control circuit which actuated the opening of the valve, thus leaving the valve free to close which it does when air pressure arrives via the upper end 40 of cylinder 13 and the pipe 65. Shutting off the air blast permits the springs 8 to reclose movable contacts 7. Movable contacts 7 are thus held open by the air blast until switch 1 has opened. Switch 3 is held open for a definite length of time (during which switch 1 has opened) and is then reclosed by its spring 3a in cylinder 3b which acts as an air dashpot to delay motion of the piston when it has moved to the right of the U tube, the leakage between piston and cylinder permitting the slow escape of air and delayed motion of piston. When the piston is between the two ends of the U tube, there is no dashpot action and no opposition to the spring in reclosing switch 3.

55 To close the circuit breaker, control switch 19 is closed, energizing coil 16 and moving slide valve 12 to the right, admitting compressed air to the lower end of cylinder 13, and causing closing of switch 1.

60 Fig. 16 shows a means for opening automatic disconnecting switch 1, which means may be used alternatively to the means shown in Fig. 1, or it may be used in conjunction with said means as an additional means to insure the prompt opening 65 of switch 1, in case of the failure of the means shown in Fig. 1. When the three valves 17 of the three interrupter units shown in Fig. 3, open simultaneously, discharging a blast of air through each of the interrupters, air pressure is 70 exerted through pipes 301, check valves 302, header-pipe 303, to diaphragm 304 and cylinder 13, tending to move its piston toward the left to open switch 1 as previously described. Under certain 75 conditions of operation, there may still be air pressure in the left end of cylinder 13, tending to

hold its piston towards the right, with reference to Fig. 16. In order to remove such opposing force, a diaphragm-opened valve is employed. This valve is normally closed and opens when pressure is exerted on its diaphragm 304, discharging air from the left end of 13 to the atmosphere through valve 305. This same air blast pressure may be used to supply pressure to pipe 65 and reclose valve 17 as elsewhere described.

Movable contacts 7 and switch 3 have already been reclosed after the preceding opening of the circuit breaker. In case there is a fault on the main line when switch 1 closes, switch 3 and movable contacts 7 are therefore in their correct fully closed position and ready to open automatically with no delay incident to completing their closing movement, and no arcing at movable contacts during the closing movement.

A common fault in air blast circuit breakers used heretofore is that when they close on a defective line the short circuit arc strikes across the contacts before there is any air blast to extinguish the arc. This is very injurious to the contacts. Under severe conditions it sometimes causes the contacts to weld together. In the case of oil circuit breakers, such premature arcing carbonizes the oil at the point where its purity and dielectric strength should be unimpaired; the rupturing capacity is thereby reduced. 30 My invention eliminates these faults by ensuring full closure of the switch 3 and of the contacts 7 before the switch 1 is closed.

The drawings of the 132 kv. and 275 kv. breakers show 3-pole breakers for 3-phase systems, 35 which is standard for such voltages. Each pole has all of the equipment diagrammatically shown in Fig. 1, except that the three poles are operated by one cylinder 13, one piston 11, one slide valve 12, etc.

The structure of the current interrupter K for each pole includes a stack of flat superposed units, each with a pair of arcing devices. Said units may be stacked up in greater or less number, in accordance with the voltage which the interrupter is required to handle. Each unit comprises a body B of insulation, recessed to define an aperture or vertical bore 25, a diffusion chamber 30 and a pair of horizontal, arcuate passages or arc chutes 26 connecting said bore and chamber. A pair of 45 arcing horns 7 are pivotally mounted within the diffusion chamber to swing horizontally and they are electrically connected and connected to swing in unison. Each horn comprises a radial arm leading from the pivotal mounting of the horn and bearing an arcuate portion which extends through one of the arc chutes 26. The bores 25 of the interrupter units are disposed in register to form a vertical air conduit leading to the top of the interrupter and closed at its upper end. The air pipe 18 is in delivery connection with the lower end of said conduit and the conduit is in lateral communication with all of the arc chutes.

The insulator bodies of the interrupter units are also recessed to shiftably accommodate L-shaped contactors 6. The latter are arranged laterally or transversely of the horns 7 and are disposed to project into the arc chutes and bear laterally against one side of the tip portion of the horns when the horns are in closed circuit position. Opposed surfaces of each horn and its cooperating contactor 6 diverge or flare toward the bore 25. A spiral spring 8 at the pivotal mounting of each pair of horns urges the horns to circuit-closing position. Each contactor 6 is 75

urged into contact with its cooperating horn by a spring 27. The resistor tap contacts 9 and 9a are spaced along the walls of the arc chutes opposed to the outer edges of the horns 7. The resistor taps comprise granular resistor material contained in an insulating tube under spring pressure, the several sections of the resistor having resistivities best suited to their sequence in the circuit. The outer edge of each horn and the opposed insulation wall having the resistor tap contacts, in effect, define a narrow arc chute, the edge of the horn forming a movable wall of the chute. For cushioning the opening movement of the horns, there are provided for each pair of horns a brake strip 28, with which the horns make wiping frictional contact, and a bumper 29.

Each diffusion chamber 30 has an air cooling grid 31, formed of thin superposed metal strips spaced very close together. The grid is disposed so that the air discharged into the chamber 30 from the arc chutes must pass through the grid on its way out of the chamber. A damper 32 is provided at the outlet of each diffusion chamber to keep out snow, dust, insects, etc. The air blast 25 opens the dampers and they close by their own weight.

The insulation body of each of the superposed interrupter units may be built up of superposed horizontal sheets of different grades of completely 30 arc-proof material, the intermediate sheets being of material selected chiefly for its high dielectric strength. The structure is held securely together by large diameter rods 30 of insulating material. These rods resist the air pressure and stresses of 35 operation. Weatherproof insulating material covers the structure and has shields 33 to prevent the formation of a continuous coating of snow, sleet, etc. The entire interrupter structure is supported by insulator stacks.

40 It is an important feature of the interrupter that the electrical stress is vertical, not horizontal. A horizontal top surface cannot be kept free from a continuous covering of snow, forming a conducting path which would cause a short circuit 45 from end to end, whereas the vertical sides can be protected by the shields above noted. Additional advantages of the vertical arrangement are: elimination of bending stress on the insulating rods, and simplification of base plate construction by the use of steel instead of insulation material.

The interrupter operates as follows: A strong 55 blast of air admitted to the pipe 18 flows into the conduit formed by the bores 25 of the interrupter units and said conduit distributes the air to all of the arc chutes. The first effect when the air blast arrives at the entrance of an arc chute is to blow the movable contactor 6 outward laterally away from the horn 7. Contactor 6 bears an auxiliary or arcing contactor 6a which separates from horn 7 slightly after 6, thereby saving 6 from being burnt by the arc. Said contactor moves away from the horn before the horn is moved by the air blast, because it has less inertia than the horn. 60 The arc resulting from said lateral movement of the contactor is blown along the narrow passage between the horn and the opposed fixed wall of the chute, having the resistor tap contacts 9 and 9a. The arc makes electrical contact with said 65 taps successively, thus shunting current away from the preceding contact and reducing the total current by the insertion of resistance in the circuit. The arc carrying the reduced current is broken when one end is blown toward the far end 70 of the horn, while the other end remains on con-

tact 9a. The conditions during that moment are ideal for the breaking of the arc, viz., the cross section of the arc cannot be greater than the narrow passage (about one-half square inch); the length of the arc (unless it is broken sooner) is 5 relatively great, extending from 9a to the far end of the horn and the full velocity and pressure of the air blast extends from end to end of the arc, thereby obtaining a maximum deionizing, or 10 reduction in conductivity, and cooling effect with a minimum quantity of air.

While the foregoing is taking place, the horn 7 is moving outward under the air pressure which overcomes the force of the spiral spring 8. The horn is shifted to fully open position in about one-hundredth of a second and it is held open by the air blast until after the disconnecting switch 1 has opened and removed voltage stress from the interrupter. There is a separation of about 15 twelve inches between the end of the horn and 20 contact 9a, which provides a liberal factor of safety against restriking of the arc in the arc chute 26. The horn in all of its positions is spaced out of contact with the tap contacts 9 and 9a.

The horns being connected in pairs, as shown, 25 the two arcs discharged from the same pair of horns are of the same electrical potential and cause no short circuit when they are blown together in the same diffusion chamber 30, one chamber for each pair of horns being provided. 30 The arcs or incandescent gases from different pairs of horns are prevented from blowing together until after they have been thoroughly mixed with the blast of cold air and thus rendered safely non-conducting. The diffusion 35 chambers accomplish this very completely by providing a large space in which turbulent action is caused by several abrupt changes in direction. The grids 31 are also a very effective cooling means.

To guard against possible condensation of moisture over the interior surfaces of the interrupter structure, a small quantity of air, which has been thoroughly dried and slightly heated, 45 is passed continuously through the interrupter, to prevent the entrance of moist air. This supply of dry air is obtained from leakage past the automatic valves, as will be described herein- 50 after, and/or directly from the main air tank 170.

The interrupter described has this fundamental advantage: The entire range of commercial transmission voltages (from 12,000 to 275,000 55 volts) can be properly served with one design of interrupter element or unit only six inches high and four feet square. A large number of these elements can be stacked up in a relatively small space. For 138,000 volts, the stack is only about forty inches high, and for 275,000 volts about 60 seven feet high. When still higher voltages are required, they can be served by simply adding a few more similar elements or units.

For the 275 kv. circuit breaker, there is provided an improved arrangement of insulator stacks to support the interrupter. For said voltage, eight standard insulators in series are required in each stack, making a height of about eleven feet, rendering such a stack relatively weak to resist bending stress (about 600 lbs. ultimate strength), whereas the stack has a 70 direct tensile strength of about 23,000 lbs. In the present structure, for greater strength, the supporting insulators are diagonally or obliquely disposed in a zig-zag arrangement around a central space beneath the interrupter. The in- 75

ulators are connected successively at their upper and lower ends alternately along the zig-zag series. This arrangement eliminates bending stress and resolves all stress into direct tension and compression and greatly increases the strength and rigidity of the supporting structure of insulators.

In the design of circuit breaker shown in Figs. 2, 3 and 4, the current transformer 4 and disconnecting switch 5 are combined by mounting 4 on a swinging bracket 104, and providing a short switch blade 5 at the lower terminal of 4, and a flexible conductor 106 from the upper terminal 4 to the interrupter terminal. The switch blade 5 is short in comparison with the supporting bracket to provide for wide opening of the switch.

The 275 kv. type of breaker has a different style of disconnecting switch 5 (see Fig. 5), in that a standard stack of insulators 105 is substituted for the current transformer on the end of the swinging bracket 104. There is also added a non-automatic disconnecting switch 20 in the line side of switch 4, for the purpose of providing the requisite distance of separation between the live line and interrupter for maintenance work. The advantage derived is that, ordinarily three insulator stacks are required for a switch of this voltage and type, whereas only two are required by the combination of switch 20 with switch 4.

The automatic valve 17 previously referred to should be capable of opening and discharging a maximum quantity of air in a minimum time, and of reclosing automatically in minimum time after the purpose of the air blast has been accomplished. The quick closing is for the purpose of minimizing waste of compressed air from the storage tank which minimizes the necessary lapse of time before the air pressure in the storage tank has been restored and the circuit breaker is ready for repeated operations. To fulfill the foregoing requirements, the valve should have the following characteristics: The opening movement of the valve should be perpendicular to the resulting cross section of air stream through the valve opening; the motion should be a minimum; the dimension of the opening perpendicular to the motion should be a maximum; the accelerating force should be a maximum; and to release and make effective the accelerating force at the proper instant, means should be provided for holding said force in restraint while the valve is to be kept closed, for discharging the restraining force in minimum time.

The invention provides for accomplishing the desired results just outlined, and others, as will appear from the following description of the valve apparatus.

Referring to Fig. 15, the storage tank 170 (not shown) is on the right hand and has a suitable permanent opening to which the valve is secured by bolting. The valve body 40 has a horizontal inlet on the right and outlet vertically upward. The valve is opened and closed by a disc 41. To facilitate explanation of the air pressures which open and close the disc, reference is made numerically to dimensions of a valve of this type which I have made and used. A stationary cylinder 42 has an internal diameter of ten inches, and a cross-sectional area of 78.5 square inches; this space 40 and 42 is normally filled with compressed air at a gauge pressure of 100 lbs. per sq. inch, which the valve exerts an

upward force of 7,850 lbs. on disc 41 to hold it closed. The narrow space 54 between the flange portions of 41 and 42 becomes normally filled with air at 100 lbs. pressure by leakage past the leather cup washers from the adjacent compressed air; the air in 54 therefore normally exerts a downward force tending to open disc 41. Disc 41 in the closed position bears against a valve-seat 55, preferably of rubber, the outside diameter of which is 7 inches. The total air pressure tending to open disc 41 is therefore 100 lbs. per sq. in. acting on an area of 49 sq. in. (area of 10 inch diameter circle less area of 7 inch diameter circle), which is 4,000 lbs. The net or resultant force holding the disc 41 closed is therefore the difference between 7,850 lbs. and 4,000 lbs., or 3,850 lbs., which is therefore the force exerted on the rubber seat 55. As the rubber seat has resilience, this force of 3,850 lbs. assists the air pressure of 4,000 lbs. to start disc 41 on its opening motion. When the disc starts to open (by discharging the compressed air in 50 and 53 to the atmosphere), the opening force of 3,850 lbs. exerted by the rubber seat ceases of course when the disc leaves the rubber, but a new opening force then begins, viz: the pressure and impact of the air as it rushes into the discharge space 56. The cone 57 secured to disc 41 is shaped to utilize the impact reaction advantageously. Guide 58 and cone 57 assist in maintaining correct alignment of disc 41 in its motion. The compressed air in space 54 expands to about six times its original volume, as disc 41 completes its opening motion, which reduces the pressure in space 54 to approximately zero (above atmosphere). This gives a maximum accelerating force at the start, tapering off to zero at the finish, which is the ideal condition.

Disc 41 is preferably made of pressed sheet metal in order to obtain the required strength with minimum mass to be accelerated. The 10-inch diameter disc weighs only about 10 lbs; assuming an accelerating force of approximately 5,000 lbs., the disc has an acceleration 500 times the acceleration of gravity.

In order to open disc 41, the compressed air in spaces 50 and 53 is discharged into the atmosphere by opening valves 60 and 61. To minimize the time required to discharge this air, the volume of spaces 50 and 53 is minimized, being practically equal to the travel of the disc 41 multiplied by the area of the 10 inch circle or 78.5 cubic inches, there being a minimum of waste space in 50 and 53. Since several valves can be opened simultaneously in the same time as one valve, it is preferred to use several valves the same as 60 to discharge the air from space 50 and one valve 61 of larger opening, to discharge the air from space 53.

The commonly available source of energy for opening and closing circuit breakers in power stations, is an electric storage battery of 125 or 250 volts. Valves 60 and 61 are operated from such a battery. The opening mechanisms of circuit breakers are usually actuated by energizing an electromagnet. Valve 61 is shown as being arranged for opening (indirectly) by energizing electromagnet 59. Valve 60 is shown arranged for opening by de-energizing its electromagnet 43, which has the advantage that an electromagnet can be de-energized more quickly than it can be energized, the time for de-energizing being only that required to extinguish the small 150 volt arc in breaking the current through the electromagnet coil, whereas the time for fully

energizing an electromagnet is determined by the necessary inductance of the coil which delays the rise of the current to its final value. Either type of electromagnet may be used with either valve 5 60 or 61.

Valve 60 has entrance ports 49 which completely surround piston 48 which closes the ports in the position shown. Electromagnet 43, having coil 44 normally carrying current, energizes magnetic 10 circuit 45 holding movable armature 46 down against its pole-piece. Breaking magnet current releases 46 and compressed spring 47 snaps piston 48 upward about $\frac{1}{8}$ ths of an inch, uncovering ports 49 and discharging the air from 15 space 50.

Valve 61 has a rubber seat 62 with an opening of $2\frac{1}{2}$ inch diameter normally closed by a metal cup 63 held up by air pressure in space 64 closed by a piston-type of valve similar to valve 60. 20 Energizing electromagnet 59 lifts the piston, discharges air from space 64 and air pressure in space 53 blows cup 63 downward $\frac{3}{8}$ inch discharging air from space 53 through an opening of 3 sq. in. cross section.

25 The automatic closing of valve 17 takes place in the following manner:

Referring again to Fig. 1, the pressure of the air blast moves piston 11 to the left admitting air pressure to the upper end of cylinder 13, 30 (opening automatic switch 1) and thence to pipe 65, which is of sufficiently large diameter (and volume) to cause a short delay in pressure rise (to allow time for switch 1 to open before the air blast is shut off). Air pressure arriving via pipe 35 65 at valve 17, enters small cylinder 66 forcing piston 48 down closing valve 60, enters cylinder 67 forcing its piston down closing the discharge from space 64, passes through check-valve 68 building up pressure in spaces 50 and 53, closing 40 disc 41, shutting off the air blast. Space 64 is refilled by air through check-valve 69 and pipe 70, thereby forcing cup 63 upward closing valve 61.

So long as switch 1 remains open, the air pressure conditions remain as just described. When 45 air pressure is admitted to the lower end of cylinder 13 (Fig. 1), (to reclose switch 1) air pressure is discharged from pipe 65 to atmosphere through cylinder 13 and slide valve 12, which leaves valve 17 ready to open automatically if and 50 when required.

In order to reduce friction of piston 48 and the piston in cylinder 67 to a minimum, no packing is used and there is a continuous slight leakage. In order to supply this leakage and maintain 55 pressure in space 50, 53 and 64 so that valve 61 and disc 41 will remain closed, a continuous supply of compressed air is taken through opening 71, pipes 72 and 73 to spaces 53 and 50, and through needle valve 74 and pipe 70 to space 64. Needle 60 valve 74 is adjusted to pass air at the minimum rate required to hold 63 closed, so as not to unnecessarily retard 63 when it opens. Leakage of high pressure air into the chamber at the under side of the valve 17 flows out through a pipe 77 65 which delivers into the air blast conduit 18, as shown in Fig. 1. By means of a valve 76, flow of said air may be adjusted to provide a continuous flow of a small amount of warm air to the interrupter to dry out its interior. The air so delivered 70 will, of course, have insufficient pressure to operate the interrupter.

Fig. 8 is an elevation (partly in section) of the current-potential transformer 2 as it is applied to a circuit breaker of the type shown in Figs. 2, 3 75 and 4. The two stacks of insulators 90 are the

same stacks 14 which support the interrupter. The insulators are of the type commonly used and have iron caps and pins, which are therefore magnetic. Steel channel 91 is part of the structure supporting the interrupter, and steel plate 92 is the baseplate of the interrupter. Pedestals 93, supporting plate 92 are iron. These existing iron and steel supports form a circuit consisting of magnetic material except the gaps of porcelain at the insulators. Coils 94, shown in section in Fig. 8 and in plan (diagrammatically) in Fig. 9, 10 are preferably made of thin wide copper bars bent into spirals, insulated from the adjacent parts. The two coils 94 are connected in series with the main high-tension circuit, the polarity of the coils 15 being such as to produce magnetic fields in the direction shown. The greater part of the induced magnetic flux follows shorter paths through the air and does not reach the bottom channel 91 and secondary coils 95 and 96. However, a sufficient 20 portion of the flux passes through coils 95 and 96 to induce a voltage suitable for operating an ordinary voltmeter or potential coil of an ordinary switchboard relay. An ordinary Weston portable voltmeter connected to one of the secondary coils 25 gives voltage readings almost exactly proportional to the current in the main high tension coils 94, i. e., the graphic relation between the high tension current and the voltage on the instrument is almost a straight line starting from zero and 30 inclined upward. A voltmeter having a scale calibrated and marked in amperes therefore gives an accurate reading of the high tension current. The voltage induced in coils 95 and 96 lags exactly 90° behind the high tension current; this 35 fixed phase relation makes this voltage suitable for use in all instruments heretofore operated by current from a current-transformer, it being necessary to replace the current coil in the instrument by a potential coil. The 90° phase relation 40 above mentioned is advantageous in connection with directional relays for opening circuit breakers when the main line current reverses on a short circuit. Short circuit currents lag almost 90° behind the line-to-neutral voltage, and the 45 induced voltage in coils 95 and 96 (being 90° behind the line current) is almost 180° behind the line-to-neutral voltage, which by simply reversing the instrument wiring, brings the two voltages in the relay almost in phase, thereby giving a 50 maximum torque for definitely controlling the directional contacts of the relay.

Coils 95 and 96 are placed in the inclined positions shown for the purpose of enclosing a portion of the leakage flux which would not otherwise 55 pass through them.

The two coils 97 are for the purpose of opposing a portion of the leakage flux thereby increasing somewhat the useful portion of the flux. Each of the coils 97 is short-circuited on itself and the 60 only current in it is that induced by the leakage flux which it opposes.

In applying the current-potential transformer 2 to the higher voltage type of circuit breaker shown in Figs. 5, 6 and 7, it is preferable to place 65 coils 95 and 96 around insulator stacks which are close together at the lower end and inclined apart at their upper ends, thereby enclosing a maximum magnetic flux.

Transformer steel laminations 98 may be secured to steel channel 91 and steel plate 92 to increase the total magnetic flux.

The transformer just described is advantageous in the higher commercial voltages (132 kv. and upward) in that its cost is very much less than 75

that of a standard current transformer because of the excessive cost of insulating parts (tubes, large porcelain cones, oil etc.) The factor of safety against electrical breakdown is also much higher.

- 5 5 The damage caused by a flashover is also negligible compared to that of a standard current transformer.

The equipment hereinbefore described may be operated by various gases instead of air, such as

- 10 carbon-dioxide, nitrogen, etc.

I claim:

1. A gas blast circuit-breaker comprising means forming a narrow arc chute including a stationary wall forming one side of the chute and an arcing

- 15 contact member forming part of the circuit and affording an opposed spaced wall forming the opposite side of the chute, said arcing member being shiftable longitudinally of the chute to make and break the circuit, an electrical contact shiftable

- 20 transversely of the chute and normally projected into engagement with an end portion of said arcing member adjacent the entrance of the chute, to make the circuit, and means to direct a blast of gas against said contact and against said end

- 25 portion of the arcing member to blow the contact away from the arcing member, blow the arc along the narrow chute space between the stationary wall and the arcing member and then blow the arcing member longitudinally of the chute to

- 30 break the circuit, said contact having less resistance to movement by the gas blast than the arcing member, whereby it will be shifted away from the arcing member before the latter is moved.

- 35 2. A circuit-breaker according to claim 1, characterized in that resilient means are provided to urge the transversely shiftable contact into engagement with the arcing member, and said means is yieldable under the force of the gas blast.

- 40 3. In a circuit-breaking apparatus including a disconnecting switch, a current interrupter in series with said disconnecting switch and operable to circuit-opening position by a gas blast, and a transfer switch in shunt with said inter-

- 45 rupter to normally conduct the current past the interrupter and operable independently of the disconnecting switch and in which said switches and interrupter are mechanically independent of each other, a gas-pressure mechanism to operate

- 50 said interrupter, transfer switch and disconnecting switch, comprising means to supply a gas blast to the interrupter to open it and break the circuit, means responsive to said blast to open the transfer switch independently of the disconnecting switch and prior to the opening of the interrupter by said blast to thereby transfer the current to the interrupter for breaking by the latter, and means responsive to the gas blast to open the disconnecting switch subsequent to the opening of the interrupter by the gas blast.

- 55 4. In a circuit-breaking apparatus including a disconnecting switch, a current interrupter in series with said disconnecting switch and operable to circuit-opening position by a gas blast, and a transfer switch in shunt with said interrupter to normally conduct the current past the interrupter and operable independently of the disconnecting switch and in which said switches and

- 60 interrupter are mechanically independent of each other, a gas-pressure mechanism to operate said interrupter, transfer switch and disconnecting switch, comprising a gas conduit to deliver a gas blast to the interrupter to open it and break the circuit, a source of compressed gas in delivery

connection with said conduit, valve means to control admission of gas from said source to said conduit, said valve means being normally closed against said admission and adapted to be opened to admit a blast of the gas to the conduit, a shiftable actuator for the transfer switch disposed in the path of the gas blast in said conduit and shiftable by impact of the gas blast to open the transfer switch independently of the disconnecting switch and prior to opening of the interrupter by said gas blast to thereby transfer the current to the interrupter for breaking by the latter, a fluid-pressure-responsive mechanism for operating the disconnecting switch, and valve means responsive to said gas blast to establish a fluid pressure connection between said source of compressed gas and said operating mechanism of the disconnecting switch independent of said conduit and said blast-control valve means, to operate said operating mechanism of the disconnecting switch to open the latter switch after opening of the interrupter by the gas blast.

5 5 5. In a circuit-breaking apparatus including a disconnecting switch, a current interrupter in series with said disconnecting switch and operable to circuit-opening position by a gas blast, and a transfer switch in shunt with said interrupter to normally conduct the current past the interrupter, and operable independently of the disconnecting switch and in which said switches and interrupter are mechanically independent of each other, a gas-pressure mechanism to operate said interrupter, transfer switch and disconnecting switch, comprising means to supply a gas blast to the interrupter to open it and break the circuit, means responsive to said blast to open the transfer switch independently of the disconnecting switch and prior to the opening of the interrupter by said blast to thereby transfer the current to the interrupter for breaking by the latter, means responsive to the gas blast to open the disconnecting switch subsequent to the opening of the interrupter by the gas blast, and means responsive to the blast to terminate the blast.

40 6. In a circuit-breaking apparatus including a disconnecting switch, a current interrupter in series with said disconnecting switch and operable for opening the circuit by a gas blast, and a transfer switch in shunt with said interrupter to normally conduct the current past the interrupter and operable independently of the disconnecting switch and in which said switches and interrupter are mechanically independent from each other, a gas-pressure mechanism to operate said interrupter, transfer switch and disconnecting switch comprising means to supply a gas blast to the interrupter to operate it to open the circuit, means responsive to said blast to open the transfer switch independently of the disconnecting switch and prior to the opening of the interrupter by said blast to thereby transfer the current to the interrupter for breaking by the latter, means responsive to the gas blast to open the disconnecting switch subsequent to the opening of the interrupter by the blast, and means to automatically close the transfer switch after the disconnecting switch has been opened in response to the gas blast and the blast has been shut off.

7. A gas blast circuit breaker comprising a plurality of similar interchangeable units directly superimposed in vertical succession and separably connected and each comprising a body of insulation having therein a plurality of horizontal arc chutes and a diffusion chamber into which the

5 discharge ends of the arc chutes open and an
arcing member in each chute shiftable by gas
blast to break the circuit, and means to direct
a blast of gas into the arc chutes of all of said
units to shift the arcing members to circuit
breaking position.

8. A gas blast circuit breaker comprising a
plurality of similar, interchangeable units directly
superimposed in vertical succession and separably
10 connected and each comprising a body of insu-
lation having therein a horizontal arc chute and a
vertical bore in lateral gas delivery communica-
tion with one end of the chute and a diffusion
chamber in receiving communication with the op-
15 posite end of the chute and an arcing member
in each chute shiftable by gas blast to break the
circuit, said bores of the different units being in
vertical register to form a conduit for delivery of
a gas blast to the arc chutes of all of the units
20 to shift the arcing members to break the circuit.

9. A gas blast circuit breaker comprising a plu-
rality of similar interchangeable units directly
superimposed in vertical succession and separably
connected and each comprising a body of insu-
25 lation having therein a horizontal arc chute and

an arcing member in the chute shiftable by gas
blast for circuit breaking, and means to direct
a gas blast into the chutes of all of the units to
shift said arcing members for circuit breaking.

10. A circuit breaking apparatus comprising 5
a current interrupter and a disconnecting switch
connected in series in a circuit, characterized in
that said disconnecting switch comprises a sta-
tionary insulator stack bearing one of the switch
contacts, a movable insulator stack bearing a 10
switch element for engagement with said contact,
a supporting arm for said movable insulator stack
pivotally mounted at one end to swing about a
vertical axis and bearing the movable stack at its
15 opposite end in close proximity to said contact
on the stationary stack when the switch is closed,
the length of said supporting arm being several
times the length of said switch element borne
by the movable stack and the arm being adapted
20 to swing about its axis more than ninety degrees
for wide separation of said switch element from
said contact when the switch is opened, and a
flexible electrical connection between said shift-
able switch element and the interrupter. 25
